Richard S. French, Waterville, Maine, assignor
to Keys Fibre Company, Portland, Maine, a cor-
poration of Maine

Application May 31, 1951, Serial No. 15,356

Term of patent 14 years

(Cl. D58—13)

To all whom it may concern:

Be it known that I, Richard S. French, a citizen of the United States, residing at Waterville, in the county of Kennebec and State of Maine, have invented a new, original, and ornamental Design for Molded Pulp Insulation Member, of which the following is a specification, reference being had to the accompanying drawing, forming part thereof, and wherein:

Fig. 1 is a plan view of a molded pulp insulation member showing my new design;

Fig. 2 is a side view of the insulation member of Fig. 1; and

Fig. 3 is a sectional view of the insulation member of Fig. 1 taken along the line 3—3.

I claim:

The ornamental design for a molded pulp insulation member, as shown.

RICHARD S. FRENCH.
